[57] CLAIM

The ornamental design for an electronic book library for storing digitized computer readable material computer, as shown and described.

DESCRIPTION

FIG. 1 is a top front and right side perspective view of an electronic book library for storing digitized computer readable material showing our new design;

FIG. 2 is a left side view thereof;

FIG. 3 is a right side view thereof;

FIG. 4 is a front view thereof;

FIG. 5 is a top view thereof;

FIG. 6 is a front view of a second embodiment thereof showing two libraries side-by-side; and,

FIG. 7 is a front view thereof in which a kiosk is shown in broken lines for illustrative purposes only and forms no part of the claimed design.
